UNITED STATES PATENT OFFICE.

WILLIAM A. WARRINER, OF FRANKLIN, GLOUCESTER COUNTY, NEW JERSEY, ASSIGNOR, BY DIRECT AND MESNE ASSIGNMENTS, OF ONE-HALF TO OLIN B. PENDLETON, OF BROOKLYN, NEW YORK, AND JESSE MYERS, OF TOWANDA, PENNSYLVANIA.

SPRING CAR-STARTER.

SPECIFICATION forming part of Letters Patent No. 293,204, dated February 5, 1884.

Application filed May 24, 1883. (No model.)

To all whom it may concern:

Be it known that I, WILLIAM A. WARRINER, a citizen of the United States, and a resident of Franklin township, Gloucester county, New Jersey, have invented an Improvement in Spring Car-Starters, of which the following is a specification.

My invention relates to certain improvements in that class of car-starters in which the movement of the axle of the car, when the latter is stopping, is transmitted to a spring-shaft and caused to effect the winding up of a spring, the recoil of which is afterward exerted to start or aid in starting the car.

The objects of my invention are to provide noiseless winding and power-transmitting gearing, to readily throw said gearing into and out of action, and to control the winding and unwinding of the spring, so as to prevent excess in either direction.

In the accompanying drawings, Figure 1, Sheet 1, is a longitudinal section of sufficient of a street-car truck to illustrate my invention; Fig. 2, a transverse section on the line 1 2, Fig. 1; Fig. 3, a transverse section on the line 3 4; Fig. 4, Sheet 2, a plan view of Fig. 1; Fig. 5, the same with some of the parts in a different position, and Figs. 6, 7, and 8 detached views of parts of the device.

A represents part of the frame or sill of a street-car truck, and B one of the axles of the same, which is provided with the usual wheels, D, with a fixed pinion, E, and with a loose chain-wheel, F.

In the rear of the axle is a shaft, G, which is adapted near one end to a bearing, a, on the frame, the shaft having a slight play in said bearing, in order to permit such movement of the opposite end of the shaft as may be sufficient to carry a spur-wheel, H, thereon into or out of gear with the pinion E of the axle. The free end of the shaft is adapted to a bearing, b, on a bar, I, the rear end of which is guided in a hanger, d, on the frame, the front end of the bar being connected to the short arm of a lever, J, which is hung to a stand, e, on the platform, the long arm of the lever being within convenient reach of the driver of the car. A spring, f, acts upon the bar I and

tends to draw the same rearward, so as to free 50 the spur-wheel H from engagement with the pinion E; but by a proper operation of the lever J the bar may be drawn forward and the wheel H thrown into gear, a catch, g, on the lever J being adapted to notches on the stand 55 e, so as to hold the lever in either of its extreme positions. An arm, K, is secured at the front end to the bar I, and bears at the rear end upon a scroll-cam, h, on the shaft G, said arm having a projecting lug, i, which can 60 be brought into the path of a pin, k, on the wheel H, in order to stop the rotation of the latter, the arm also serving, by engagement with a hooked arm, m, on the shaft G, to stop the rotation of said shaft in the opposite direction, as described hereinafter. The connection of the arm K with the bar I is such as to permit the elevation and depression and also the lateral movement of the rear end of 65 said arm under control of the scroll-cam h. 70

Hung to the arm K is a plate, n, the lower end of which is hooked, so as to embrace the axle B, said plate bearing against the hub of a disk, M, on the axle, and having cams w, adapted to engage with a collar, s, on said 75 axle as the plate is raised. The disk M is held in contact with the plate n at all times by means of a spring, p, and on said disk are pins t, which pass through openings in the pinion E, and act upon springs x, projecting from 80 pawls y, hung to lugs on the face of said pinion, the outer ends of the pawls being adapted to engage with the face of the chain-wheel F.

On the shaft G is a chain-wheel, N, connected by means of a chain belt, P, to the wheel F, and to the said shaft G is secured one end of a coiled spring, W, the opposite end of which is secured to some fixed part of the frame.

The operation of the device is as follows: When the car is running, the parts are in the 90 position shown in Figs. 5 and 6, the spring being unwound or partially unwound, the wheel H out of gear with the pinion E, and any movement of the shaft G, under control of the spring, prevented by the contact of the arm m with the arm K. The latter arm being fully depressed, the plate n is lowered, as in Fig. 6, and the disk M is thrust by the 95

spring p away from the pinion E , thus removing tension from the springs x , and permitting the pawls y to remain free from contact with the wheel F , so that there is nothing to prevent either forward or backward movement of the car. When it is desired to stop the car, the driver operates the lever J , so as to draw the bar I forward and hold it in this position, the lever being locked by means of its catch g . The wheel H is thus brought into gear with the pinion E , and the shaft G is turned so as to wind up the spring W . At the same time, under the influence of the scroll-cam h , the rear end of the arm K is raised and moved laterally toward the wheel H , this movement, unless the car stops in the meantime, being continued until the pin k of the wheel comes into contact with the lug i on the arm and locks said wheel, as shown in Fig. 4. The elevation of the arm K raised the plate n and brought the cams w to bear on the collar s of the axle B , as in Fig. 7, the disk M being thereby thrust toward the pinion E , so that the pins t impart tension to the springs x and cause the pawls y to bear firmly against the wheel F . When it is desired to start the car, the lever J is released, and the bar I is drawn rearward by means of the spring f , so as to throw the wheel H and pinion E out of gear. The shaft G is now free to turn under the influence of the unwinding spring, the movement being transmitted, through the medium of the wheels N and F , belt P , pawls y , and pinion E , to the axle B , which is caused to turn forward, and thus start the car. As the shaft G turns forward, the rear end of the arm K , under control of the scroll-cam h , is moved laterally away from the wheel H until, finally, it comes within the path of the arm m , and thus stops the further movement of the shaft G , as shown in Fig. 5. At the same time the end of the arm drops, so as to lower the plate n and its cams and permit the movement of the disk M away from the pinion E , so as to remove the tension from the pawls y and withdraw said pawls from contact with the wheel F , as before.

By properly proportioning the wheels H and N in respect to the pinion E and wheel F , the power represented by the momentum of the car and stored up by the mechanism described in stopping the car may be applied with greatly increased effect to the starting of the car. For instance, three or four turns of the axle B may be made in winding up the spring W in stopping the car, and the power of the spring may be expended in effecting a single revolution of the axle in starting.

The duties of the driver of the car are not increased by the use of the starting mechanism, as in most cases the use of the brake will not be needed, and the operation of the lever J can be effected more readily than the turning of the brake-handle.

I claim as my invention—

1. A spring car-starter in which the axle B , having a chain-wheel, F , and pinion E , with pawl-connection, is combined with a spring-shaft, G , having chain-wheel N and spur-wheel H , a belt, P , and means for moving said shaft so as to throw the wheel H into and out of gear with the pinion E , as set forth. 65

2. The combination of the axle B , the wheel F , the pinion E , and the spring-pawls y , carried by the pinion and bearing on the wheel, with the spring-shaft, its wheels H and N , and the belt P , as set forth. 75

3. The combination of the axle B , the wheel F , the pinion E , the pawls y , hung to said pinion and having arms x , and the adjustable disk M , having pins t , for acting on said arms, as set forth. 8c

4. The combination of the axle B , the wheel F , pinion E , the pawls y and their arms x , the disk M and its pins t , and a cam-plate, n , for adjusting said disk, as set forth. 85

5. The combination of the axle B , its wheel F and pinion E , the spring-shaft G , its wheel N and spur-wheel H , the belt P , the bar I , carrying one end of said shaft G , the spring f , and the lever J , for acting on said bar I , as specified. 90

6. The combination of the spring-shaft G , having a scroll-cam, h , and stop-arm m , with the arm K under control of said scroll-cam, as set forth. 95

7. The combination of the spring-shaft G , having a scroll-cam, h , and wheel H , with stop-pin k , with the arm K , controlled by the cam h , and having a stop-lug, i , as set forth. 100

8. The combination of the axle B , the pinion E and its pawls, the disk M , having pins acting on said pawls, the shaft G , having a cam, h , and the arm K , controlled by said cam h , and having a cam-plate, n , for actuating the disk M , as set forth. 105

In testimony whereof I have signed my name to this specification in the presence of two subscribing witnesses.

WILLIAM A. WARRINER.
